US00D966027S

(12) **United States Design Patent** (10) **Patent No.:** **US D966,027 S**
(45) **Date of Patent:** **** Oct. 11, 2022**

(54) **APPLIANCE FOR PREPARING AND DISPENSING FOAMED FLUID FOOD**

(71) Applicant: **ISI GMBH**, Vienna (AT)

(72) Inventor: **Dominik Meier**, Munich (DE)

(**) Term: **15 Years**

(21) Appl. No.: **35/512,947**

(22) Filed: **May 19, 2021**

(80) **Hague Agreement Data**

Int. Filing Date: **May 19, 2021**

Int. Reg. No.: **DM/215029**

Int. Reg. Date: **May 19, 2021**

Int. Reg. Pub. Date: **Nov. 19, 2021**

(57) **CLAIM**

The ornamental design for an appliance for preparing and dispensing foamed fluid food, as shown and described.

DESCRIPTION

1. Appliance for preparing and dispensing foamed fluid food

1.1 : Bottom

1.2 : Side

1.3 : Rear

1.4 : Front

1.5 : Top

1.6 : Perspective

1.7 : Side

Appliance for preparing and dispensing foamed fluid food, comprising a replaceable sleeve in the middle of the container of the appliance.

1 Claim, 7 Drawing Sheets
